(Cl. D44—8)

To all whom it may concern:

Be it known that we, Walter C. Kelley and Herbert C. Phillips, both citizens of the United States, and both residing at Los Angeles, in the county of Los Angeles and State of California, have invented a new, original, and ornamental Design for a Mixer for Frozen Desserts, of which the following is a specification, reference being had to the accompanying drawing, forming part thereof, in which:

Fig. 1 is a front perspective view of a mixer for frozen desserts, showing my new design;

Fig. 2 is a side elevational view; and

Fig. 3 is a top plan view thereof.

We claim:

The ornamental design for a mixer for frozen desserts, substantially as shown.

WALTER C. KELLEY.

HERBERT C. PHILLIPS.
